UNITED STATES PATENT OFFICE

ALBERT HENDERSON, OF PITTSBURGH, PENNSYLVANIA, ASSIGNOR TO HENDERSON AND HATCHER, INC., OF PITTSBURGH, PENNSYLVANIA, A CORPORATION OF DELAWARE

RAILWAY TRACK SYSTEM

Application filed October 24, 1929. Serial No. 402,032.

My invention relates to railway track systems, and more particularly to concrete road beds for railway track systems.

It has been customary in the past to use spaced cross ties of concrete or wood to support spaced railroad rails. Recently, due to the increased weight of locomotives and truck equipment, such spaced cross tie construction has necessitated the use of heavier rails to support the increased weight; the heavier rails operating to distribute the heavier load over more cross ties.

This practice is very expensive due to the higher cost of the heavier rails, but it does not solve the problem involved because of the fact that, to a very small extent, each wheel travels up-hill between ties, taking up more than 10% of the motive power of the locomotive. Another serious disadvantage to this construction resides in the possibility of broken rails due to the flexural strains caused by the loaded wheels continually bending the rails. Sometimes broken rails result in serious disasters to passenger express trains.

With the spaced cross tie construction it is also necessary to maintain the expensive work of continuously levelling and alining the tracks.

My invention provides a track system that is not subject to the above disadvantages and, in addition, permits the use of a much lighter and therefore less expensive rail in comparison with the rails required in the spaced cross tie construction.

My invention provides a plurality of concrete units assembled together to form a road bed having a substantially unbroken rail supporting surface whereby a moving wheel load subjects the rail to compression only, the flexure or beam action being substantially entirely eliminated.

My invention may be more readily understood if the accompanying drawings are referred to in connection with the following description.

Figure 1 is a plan view of a rail supporting road bed constructed in accordance with my invention;

Figure 2 is a view in side elevation of the road bed illustrated in Fig. 1;

Figure 3 is a view in elevation, and partially in cross-section, of a complete track system utilizing the road bed illustrated in Figs. 1 and 2;

Figure 4 is an enlarged view showing in dotted lines the reinforcing of the rail supporting girders illustrated in Figs. 1 and 2;

Figure 5 is an elevational view of a reinforced concrete cross tie for the rail supporting girders;

Figure 6 is a top plan view of the cross tie illustrated in Fig. 5;

Figure 7 is a perspective view of a wedge for holding the cross ties and girders in assembled relation;

Figure 8 is a cross-sectional view of a modification of a railway track system;

Figure 9 is a view in side elevation of a portion of the track system illustrated in Fig. 8;

Figure 10 is a cross-sectional view of a modification of a track system particularly applicable for street railways;

Figure 11 is a top plan view of a portion of the street railway track system illustrated in Fig. 10;

Figure 12 is a view in end elevation of the track system illustrated in Fig. 11;

Figure 13 is an enlarged cross-sectional view of the rail shown in Fig. 11;

Figure 14 is a sectional view taken on the line XIV—XIV of the rail shown in Fig. 13;

Figure 15 is a cross-sectional view of a further modification of a railway track system;

Figure 16 is a view in elevation of a cross tie used in the track system modification illustrated in Fig. 15;

Figure 17 is a view in cross-section of a modification of a rail supporting girder;

Figure 18 is a view similar to Fig. 17 of a further modification of the rail supporting girder;

Figures 19, 20 and 21 are views similar to Fig. 17 of further modifications of the rail supporting girder;

Figure 22 is a cross-sectional view of a rail supporting girder made in two parts having

recesses for supporting and clamping the lower part of the rail in position; and

Figure 23 is a view similar to Fig. 10 of a modification for securing the rail guard to the concrete cross ties.

Referring to Figs. 1 to 7, inclusive, a plurality of pre-cast reinforced concrete members 1, 2, 3, 4 and 5 of substantially rectangular cross-section are arranged in two parallel lines in end-to-end relation so that a substantially unbroken upper surface is presented for supporting a plurality of spaced rails 6 and 7. The parallel lines or supporting girders 8 and 9 formed by the concrete members 1 to 5, inclusive, may be, and preferably are, laid on and supported by spaced concrete foundations 10 and 11.

The concrete members forming the rail supporting girders 8 and 9 are provided with a plurality of spaced openings 12 of similar size. These openings not only decrease the weight of the reinforced concrete members, but they also provide for the accommodation of the ends of reinforced concrete cross ties 12', 13 and 14. The cross ties comprise a central rectangular body 15 provided with extensions 16 and 17 of reduced size for extension through the openings 12 in the concrete rail supporting members.

Openings 18 are provided in the ends 16 and 17 for the accommodation of a reinforced concrete wedge 19. The latter is provided with a horizontal hole 20 for the reception of a pin 21 for holding the wedge 19 in position.

The cross ties are also provided with openings 22 for lightening the structure and for the accommodation of conduits, such as electric signal cables, (not shown).

As clearly illustrated in the drawings, the various pre-cast cementitious units used in the construction of the track system are provided with steel reinforcing means 23 for increasing the strength thereof.

The rails may be secured to the supporting girders 8 and 9 by means of angles 24 secured by bolts 25 to the girders in such manner that the lower flanges of the rail are firmly secured to the continuous supporting surface of the girders. The angles 24 may be continuous or they may be spaced any desired distance apart along the lower flanges of the rails.

Where the bolt and angle construction for holding the rails in position is used, as illustrated in Fig. 3, the pre-cast concrete members 1 to 5, inclusive, are provided with vertical openings 26 for the reception of the bolts 25. The openings 26 extend from the horizontal openings 12 to the upper and lower surfaces of the concrete members.

The concrete supporting members used for the rail supporting girders may be pre-cast in any desired shape to accommodate different types of rails, as shown in the modi-

fications illustrated in Figs. 17 to 22, inclusive.

Referring to Fig. 17, there is illustrated a concrete girder 28 provided with a plurality of horizontal shoulders for the accommodation of a simple rail 29 of rectangular cross-section that is secured in position on the upper shoulder by means of a bolt 30. As in this type of construction where light loads are transmitted to the rail 29 through a wheel 31, the concrete girder 28 may be laid directly on the ground 32.

As shown in Fig. 18, the rail 33 may be inserted in a corresponding slot 34 provided in the rail supporting surface of the girder 30 where light loads are to be carried.

Referring to Fig. 19, a steel support and guard 36 for a street railway rail 37 may be mounted directly on the girder 38 and secured thereto by means of bolts 39. The rail 37 may be secured to the support and guard 36 by means of bolts 40 that are spaced apart along the track. In this case it is necessary to provide only a single row of vertical openings 40 extending from the inside to the outside of the girder 38.

In this connection it will be noted that the girders are constructed so that their upper and lower surfaces are reversible, thereby facilitating the laying of the track system.

As shown in Fig. 20, the girder 41 may be provided with a recess 42 for the reception of a rail 43 having an integral guard flange 44. In this modification the sides and bottom of the rail are provided with a large supporting area. Spaced bolts 45 may be used to hold the rail 43 in position with respect to the girder 41.

As shown in Fig. 21, which is somewhat similar to Fig. 19, the rail 46 may be provided with a recess 47 for accommodating the head of a bolt 48 that extends above the surface of the rail guard 49. The construction of the rails and rail guards illustrated in Figs. 19 and 21 will be discussed more fully below.

Referring to Fig. 22, there is illustrated an important modification of my invention. The supporting girder in this case is made in two halves, 50 and 51, respectively, each of which is provided with a corresponding recess 53 for the reception of the lower horizontal flange and a portion of the vertical section of a rail 54 of substantially I-shape. The wedge 55 coacting with the concrete cross tie 56 holds the halves 50 and 51 and the rail 54 firmly together in assembled relation. All bolts, nuts, plates and the like for holding the rails in position on the supporting girders are eliminated by the modification illustrated in Fig. 22.

Referring to Figs. 8 and 9, a somewhat similar modification for holding the rails 57 and 58 in position is illustrated. In this case the continuous beams 59 and 60 are supported on spaced concrete cross ties 61, 62 and 63.

63. The cross ties are provided with rectangular recesses 64 for the reception of the beams or girders 59 and 60. The beams 59 and 60 are split in half for the reception of 5 the rails in a manner similar to that described above in connection with the modification illustrated in Fig. 22. Lifting arms 65 are cast into the beams 59 and 60 for the purpose of lifting the beams out of the recesses 64 in 10 the cross ties for the purpose of repair or replacement. Suitable recesses 66 are provided in the side walls of the cross tie openings 64 for the vertical movement of the arms 65 in raising and lowering the beams. 15 It will be noticed also in connection with Figs. 8 and 9 that no spikes or connecting rail plates are necessary to hold the rails in position.

Referring to Figs. 10 to 13, inclusive, a 20 street railway track system is provided comprising a plurality of reinforced concrete ties 67, 68 and 69 disposed in abutting relation with respect to each other to form a substantially unbroken rail supporting surface for a 25 plurality of spaced street car rails 70 and 71. The cross ties are provided with recesses 72 in the bottom thereof for coaction with a plurality of cast-in-place spaced concrete foundations 73 and 74. The space below the cross 30 ties and between the foundations may be used to house a conduit system 75.

The cross ties 67, 68 and 69 are provided with recesses 76 in the upper corners thereof so that when the cross ties are placed together 35 side-by-side the opening formed by the recesses 76 may be filled with cement or grouting to form a smooth street surface.

Channels 77 and 78 for the rails 70 and 71 are cast in place when the cross ties are mold- 40 ed. The channels 77 and 78 are provided with projections 79 and 80 that are embedded in the concrete of the cross ties to hold the connecting channels in place. The ends of the cross ties are beveled so that they can be 45 easily jacked up without disturbing the adjoining road bed 81.

The sides of the cross ties are provided with vertical recesses for forming openings 82 so that should there be a settlement of the 50 track system, jacks can be introduced in the openings under the rails and resting on the foundations 73 and 74 to raise the ties so that grouting or asphalt may be poured and distributed between the cross ties and the 55 foundations.

Continuous horizontal recesses 83 are provided in the upper surface of the cross ties for facilitating the installation and removal of nuts 84 that are threaded to bolts 85 projecting from the rails.

Asphalt may be poured in the recesses 83 to cover the heads of the bolts 85 and the nuts 84. In order to prevent the asphalt from entering the vertical recesses 82 below the bottom 60 of the horizontal recesses 83, metallic

strips 86 may be inserted in the bottom of the recesses 83. In case it is necessary to have access to the nuts 84 for the purpose of loosening the rails, as for example, where it is desired to reverse the rails to present a new 70 wearing surface, the asphalt may be easily dug out of the recesses 83.

In this connection it is to be noted that in the present rail construction all four corners of the rail can be utilized, the rail being 75 preferably constructed of upper and lower sections 87 and 88, respectively, that are separated from each other by rectangular strips 89 that are spaced to form openings 91 through the sections for the bolts 85 and are 80 preferably spot-welded to the upper and lower sections of the rail.

The supporting channels are provided with corresponding openings 90 that match the 85 openings 91 in the rail.

An asphalt-asbestos strip 92 is placed between the horizontal and vertical sides of the rail and channel to absorb vibration and reduce noise when a street car passes over the 90 rails.

In case the street car is used in open country where paving over the road bed is not required, constructions similar to those illustrated in Figs. 19 and 21 may be utilized.

Referring to Fig. 19, the channel 36 may 95 be mounted on the surface of the rail supporting beam 38 and held in position as shown by the bolts 39. In this case the rail 37 may be removed for reversal by simply unloosening the bolts 85. Referring to Fig. 21, 100 which is a further modification, the rail guard 49 and the rail 46 are provided with a coacting projection 87 and slot 89 for insuring the retention of the rail in the channel.

It will be apparent that the rail 46 may be 105 solid and provided with spaced openings for the reception of the retaining bolts.

Referring to Figs. 15 and 16, a track system is shown constructed of a plurality of reversible cross ties 93. The cross ties 93 are 110 preferably of pre-cast reinforced concrete and are provided with recesses 94 for the reception of spaced concrete foundations 95 and 96. The upper surface of the ties 93 is provided with rail supporting surface plates 115 97 that are cast in place during the molding process of the cross ties. Projections 98 and recesses 99 are provided for coaction with the lower flange and one side of the vertical portion of the rails 100 and 101. Alternate cross 120 ties are positioned with the projections 98 extending in opposite directions so that the rails 100 and 101 are securely clamped in position after the various parts are assembled together.

In this construction no bolts, spikes or retaining plates are necessary to hold the rails in position. Wooden planks 102 may be placed between the upper and lower surfaces of the cross ties and supporting foundations 13

95 and 96, respectively, to absorb shocks and provide a certain amount of resiliency to the track system.

In case it becomes necessary to re-level the track system, it is an easy matter in such construction to jack up the cross ties and introduce more or thicker planks between the cross ties and the foundation.

Members 115 positioned in spaced openings 116 (Figure 16) in the cross ties 93 project out of the outer sides of the recesses 94 for coaction with corresponding recesses 104 in the foundations 95 and 96, thereby preventing upward movement of the track system with respect to the foundations. The cross ties are reinforced by cast-in steel members 103.

If for any reason it becomes necessary to remove one or more of the cross ties 93, the same may be accomplished readily by removing the pins 115 and by elevating the system above the foundations and then pulling out the cross ties from one side, or endwise.

A modification of the street railway track system is illustrated in Fig. 23. Here the cross ties 105 are provided with recesses 106 in their upper surface, in which the rail channels 107 are secured by bolts 108. Vertical recesses are provided in the sides of the concrete cross ties 105 which coact with each other to form an opening 109 for the reception of a lifting jack, as described above in connection with Figs. 10 to 13, inclusive. In this case, also, the surface of the system may be covered by a layer of asphalt 110.

A desirable feature of my invention resides in the use of a plurality of pre-cast cementitious units to form a substantially continuous supporting surface for the rails of a track system.

The use of reinforced concrete members that are pre-cast before being assembled in the track system results in a very material saving in cost as compared with a solid concrete road bed on which the rail is directly mounted.

Other desirable advantages of my invention arise by virtue of a track system that may be constructed without the use of bolts, nuts, and the like for holding the rails in position.

Another distinct advantage of a track system constructed in accordance with my invention resides in the mobility and facility for removing and replacing it after a finished installation. In this connection it is to be noticed that heretofore, especially in street railway track systems, it has been customary when replacing the rails to dig up the whole road bed and reconstruct an entire new track system at a huge expense in comparison with my facilely replaceable track system.

While I have shown and described present preferred embodiments of my invention, it is to be understood that the same is not

limited thereto but may be otherwise embodied within the scope of the following claims.

I claim:

1. In a track system, spaced rails and pre-cast concrete cross ties assembled together to form a substantially continuous supporting surface for said rails, said cross ties having corresponding recesses in their sides to provide an opening for the introduction of lifting means.

2. A track system comprising spaced rails and means for supporting said rails, comprising pre-cast concrete cross ties placed side-by-side to form a substantially continuous supporting surface for the rails, said cross ties having grooves in the upper corners thereof for forming openings for the introduction of a surfacing material.

3. In a track system, spaced foundations, reinforced concrete ties having recesses for said foundations, said ties resting on said foundations in said recesses, and spaced rails secured to said concrete ties.

4. A track system comprising spaced rails, a plurality of reinforced concrete members for supporting said rails, said members having recesses therein, and channels mounted in said recesses, said rails being secured to said channels.

5. A track system comprising a plurality of spaced rails, and a plurality of pre-cast concrete members for supporting said rails, said members having metal seats cast therein for coaction with said rails.

6. A track system comprising spaced rails, a channel member supporting each of said rails, a concrete member for supporting each of said channel members, and means for removably securing said rails to said channel members.

7. A track system comprising spaced rails, the surfaces of said rails being reversible, and supporting channels for said rails, said channels being reversible.

8. A track system comprising spaced rails, seating channels for said rails, pre-cast reinforced concrete cross ties for supporting said channels, said cross ties being arranged to form a substantially continuous supporting surface, and means substantially flush with the top of the rails covering said cross ties.

9. A track system comprising spaced rails, a substantially unbroken channel for each of said rails, and a substantially continuous supporting foundation for each of said channels.

10. A track system comprising a plurality of spaced supports, concrete cross ties having recesses for the reception of said supports mounted thereon, and rails carried by said cross ties.

11. A railway road bed comprising spaced concrete foundations, precast concrete cross ties having spaced upper and lower recesses for receiving metal channels and the upper

portion of said foundations respectively, metal channels cast-in-place in the upper recesses of said cross ties, said cross ties being positioned on said foundations with the lower 5 recesses fitting over the upper portion of the foundations in close side-by-side relationship and rails removably secured to said channels.

12. A railway road bed comprising concrete foundations, precast concrete cross ties having spaced upper and lower recesses for receiving metal channels and the upper portion of said foundations respectively, said cross ties also having recesses in the sides 10 thereof extending between the upper and lower recesses, metal channels cast-in-place in the upper recesses of said cross ties, said cross ties being positioned on said foundations with the lower recesses fitting over the 15 upper portion of the foundations in close side-by-side relationship and reversible rails of rectangular section removably secured to said channels.

13. A railway road bed comprising spaced 20 concrete foundations, precast concrete cross ties having spaced upper and lower recesses for receiving metal channels and the upper portion of said foundations respectively, said cross ties having recesses in the upper corners 25 thereof extending from end-to-end of the cross ties, metal channels cast-in-place in the upper recesses of said cross ties, said cross ties being positioned on said foundations with the lower recesses fitting over the upper portion 30 of said foundations in close side-by-side relationship, a layer of surfacing material covering the cross ties and projecting into the openings formed by said corner recesses and reversible rails of rectangular section 35 removably secured to said channels.

14. A track system comprising a substantially continuous foundation having spaced recesses, rails secured to said foundation in said recesses and a substantially continuous 45 asphalt covering over said foundation substantially flush with the tops of said rails.

15. A track system comprising a substantially continuous foundation having spaced recesses, and four-way rails detachably secured to said foundation in said recesses.

16. A track system comprising spaced metal rail supports having guides for wheel flanges, and rectangular rails detachably secured to said metal supports.

55 17. A track system comprising a guide for a wheel flange, and a rail detachably secured to said guide.

18. A track system comprising a substantially continuous foundation, a guide for a 60 wheel flange detachably secured to said foundation, and a rail secured to said guide.

19. A track system comprising a substantially continuous foundation, a substantially continuous foundation carried by said first-named foundation, and spaced rails carried

by said second-named foundation, the second-named foundation having openings to permit the entry of elevating means so that said spaced rails may be elevated.

20. The method of building a street car track system consisting of laying a continuous concrete road bed, having spaced recesses, placing in said recesses metal guides for wheel flanges, then detachably securing rails to one side of said guides and pouring asphalt 70 in the recesses covering the ends of the securing means which secure the rails to the guides so that the rail when worn may be easily detached without disturbing the guide or the foundation.

80 21. The method of building a street car track system which consists in building a substantially continuous foundation detachably securing spaced car wheel guides to said foundation, detachably securing to said guides a reversible rail head and then covering said foundation with a surface of asphalt substantially flush with the top of the rail guide and the rail.

85 In testimony whereof I have hereunto set my hand.

ALBERT HENDERSON.
